United States Patent Office

Des. 187,878
Patented May 10, 1960

187,878

GEM SETTING OR SIMILAR ARTICLE

Jules J. Roskin, Westport, N.J.

Application January 11, 1960, Serial No. 59,004

Term of patent 14 years

(Cl. D45—1)

Fig. 1 is a top plan view of a gem setting showing my new design;

Fig. 2 is a side view thereof; and

Fig. 3 is a sectional view taken along line 3—3 of Fig. 1.

I claim:

The ornamental design for a gem setting or similar article, substantially as shown.
